UNITED STATES PATENT OFFICE

133,901

DESIGN FOR A RUG

Helen Martin King, Beebe, Ark.

Application November 10, 1941, Serial No. 104,106

Term of patent 3½ years

To all whom it may concern:

Be it known that I, Helen Martin King, a citizen of the United States of America, residing at Beebe, in the county of White and State of Arkansas, have invented a new, original, and ornamental Design for Rugs, of which the following is a specification, reference being had to the accompanying drawing, forming part thereof.

The figure is a plan view of a rug, showing my new design.

I claim:

The ornamental design for a rug, substantially as shown.

HELEN MARTIN KING.
